UNITED STATES PATENT OFFICE.

HOWARD B. MINNICK, OF CHICAGO, ILLINOIS.

TOY MOLD.

1,317,093.

Specification of Letters Patent. Patented Sept. 23, 1919.

Application filed February 17, 1919. Serial No. 277,564.

To all whom it may concern:

Be it known that I, HOWARD B. MINNICK, a citizen of the United States, residing at Chicago, in the county of Cook and State 5 of Illinois, have invented a certain new and useful Improvement in Toy Molds, of which the following is a specification.

My invention relates to that class of toys which are designed, not only to entertain 10 the children by amusing them, but which will also be of value in instructing the children in the fundamentals of building.

My invention has for its object to provide a toy in which an innumerable number 15 of various sizes and configurations of building material can be reproduced with the same device by varying the position of the different members.

My invention may be more readily understood by having reference to the accompanying drawings which are hereunto annexed and are a part of this specification, in which:

Figures 1 and 2 are plan views of my new 25 invention.

Fig. 3 is a sectional view taken on the line 3—3 in Fig. 1.

Similar reference numerals refer to 30 similar parts throughout the entire description.

As shown in the drawings, the device comprises a mold or pallet board 1, which is adapted to receive two sectional mold members 2 and 3 in the position shown in 35 Fig. 1. The adjacent or mating edges of the members 2 and 3, have cut or formed thereon, a plurality of various shapes for making tile corresponding to the usual configurations of tile, while the opposite edges 40 7 and 8 are provided with recesses which will form miniature bricks, it being apparent that the members 2 and 3 can be reversed in position so that the edges 7 and 8 will be the mating edges.

45 The pallet or mold board 1, is provided with an upwardly extended shoulder 9 at one side, which serves as an abutment for the mold members 2 and 3, which are held securely in position by a latch 10 which is 50 eccentrically mounted upon a pin 11, which is rotatably mounted in the pallet or mold board 1, it being apparent that when the latch is in the position shown in dotted lines in Fig. 1, that the mold members 2 and 3 55 can be moved freely, while a slight turn of

the latch in the position shown in full lines in Fig. 1, holds them securely in position so as to insure a perfect brick being molded.

By loosening the mold members 2 and 3 and reversing their edges, it will be apparent, as shown in the dotted lines in Fig. 1, that one can produce a plurality of miniature bricks. It is also apparent, as shown in dotted lines that the mold members move longitudinally of each other and thus permit, not only of the molding of half bricks, but also of quarter bricks. They can also be reversed so as to form various shapes and styles of pilasters.

I provide a third mold member 12 as 70 shown in Fig. 2, in which the recesses are larger than the half sections of the bricks, so that pieces of larger size can be manufactured. It will also be observed that the upper portion of these can be varied. They 75 can be, as desired, either a semi-circular, square, polygonal, or half diamond shaped, just as the young artist desires, which is most suitable for the building under construction.

A recess which forms a parallelogram so 80 as to provide columns to be used in various parts of the building and a member 13 which is added, is loosely mounted in the said recess 14, permits the formation of mitered ends of the blocks formed in the recess 14.

The operation of the device, as is apparent from the hereinafter contained description, is as follows:

The child places the mold members 2 and 3 in juxtaposition with the mating edges, forming a plurality of various shaped objects. Care should be taken that one of the projecting parts is adjacent the latch 10 so that, as illustrated, it can be tightly held 90 in position. The forms are then filled with plastic material, preferably cement, which is permitted to harden. When the latch is moved the mold members are lifted from the mold or pallet board 1, and by separating them, the molded tile or brick, as the case may be, drops freely from the forms.

It will be apparent from the foregoing description, it is possible for a child to construct practically all of the various shapes required in building a quite pretentious structure; at the same time it will also be apparent that it, to a degree, teaches him the elementary principles of geometry, as he quickly learns how to form a variety of 110

shapes and angles to produce the required shape from the material.

Although I have described and illustrated the device as adapted to a single pair of mold members, it will be apparent that the mold or pallet board can be made sufficiently large so as to receive three or more mold members, thus permitting the child to form a large number of bricks or tile at one time.

10 Having described my invention, what I regard as new and desire to secure by Letters Patent, is:

1. A mold for plastic material comprising a plurality of forming devices of a thickness of which it is desired to mold the material, there being a plurality of rectangular recesses in one edge of the device and a plurality of variegated recesses in the opposite edges whereby the shapes of the molded article may be multiplied without requiring additional devices.

2. A mold for plastic material comprising a plurality of forming devices of a thickness of which it is desired to mold the material; there being a plurality of rectangular

recesses in one edge of the device and a plurality of variegated recesses in the opposite edges whereby the shapes of the molded article may be multiplied without requiring additional devices, a mold board having an abutment thereon against which said forming devices abut, and a latch to hold said devices tightly in contact with each other.

3. A mold for plastic material comprising a plurality of forming devices of the thickness of which it is desired to mold the material, there being a plurality of various shaped recesses in the mating edges of the mold members, a mold board having an abutment thereon against which said forming devices abut, and an eccentric latch mounted upon a pin or pivot mounted in the mold board which is adapted to hold said forming devices tightly in engagement with each other and the abutment for the purpose set forth substantially as described.

In testimony whereof I have signed the foregoing specification.

HOWARD B. MINNICK.
